UNITED STATES PATENT OFFICE

2,030,259

INSECTICIDE SPRAYER

Albert R. Lavitt and Homer L. Pearson,
Denver, Colo.

Application May 15, 1934, Serial No. 725,682

3 Claims. (Cl. 299—87)

SEARCHED AND SERIALIZED

This invention relates to a sprayer or atomizer, more particularly designed for spraying insecticide upon the plants in greenhouses, conservatories and the like.

5 The principal object of the invention is to provide a device of this character which can be permanently affixed to the steam heating pipe mains of a greenhouse so that the heating steam can be employed for atomizing, diluting, and spraying 10 the insecticide.

Other objects of the invention are to provide 15 a device of this character which, while permanently installed, can be moved or directed to cover a wide area; in which bottles or containers of insecticide can be easily and quickly placed in position; which will occupy but a minimum of space when in use; and which will be neat, compact, and economical to manufacture.

20 Other objects and advantages reside in the detail construction of the invention, which is designed for simplicity, economy, and efficiency. These will become more apparent from the following description.

25 In the following detailed description of the invention reference is had to the accompanying drawing which forms a part thereof. Like numerals refer to like parts in all views of the drawing and throughout the description.

30 In the drawing:—

Fig. 1 illustrates the improved insecticide sprayer as it would appear when attached to the steam main of a greenhouse or similar installation.

35 Fig. 2 is a side elevation thereof, partly in section, illustrating the interior construction.

A typical steam main pipe such as used in greenhouses is indicated at 10. The invention comprises a tubular head member 11, closed at its top by means of a removable screw cap 12. The head 11 is supported upon a valve housing 13 by 40 means of a suitable union nut 14.

The valve housing carries a valve 15 by means of which the supply of steam to the head may be controlled. The entire device is supported upon a nipple 16 extending from the main 10. If necessary a reducing fitting 17 may be employed to seal the valve housing 13 to the nipple 16.

45 A blow pipe 18 extends outwardly at a slight upward angle from the head 11 and terminates in an atomizing shield 19. The atomizing shield supports a suction tube 20. The discharge opening of the blow pipe 18 is positioned opposite the discharge orifice of the suction tube 20 to obtain a suction and vacuum effect at this point similar

to the usual atomizer. The suction tube 20 passes through a guide ear 21 on the shield 19 and is rigidly supported in place by means of a post 22 secured to the shield.

5 A bracket member 23 extends from the head 11 outwardly and downwardly to support a suitable container or bottle 24 in which the insecticide or other material to be atomized is carried. The suction tube 20 extends downwardly into the bottle 24 through a threaded bottle cap 25, which 10 is provided with a funnel-like depression 26 about the tube 20. The bracket member 23 is preferably formed with a downwardly extending bottom hook 27 which extends beneath and supports the bottle 24 in place. It is preferred to form the 15 bracket member 23 of spring metal so that, after removing the cap 25, the bottle can be removed or replaced by springing the hook 27 to one side.

In use the union nut 14 need not be screwed 20 to a tight clamping position, but may allow sufficient looseness so that the head 11 can be rotated to project the blow tube 18 in any desired direction. A screen 28 is positioned in the head 11 to screen foreign materials from the incoming steam. A suction screen 30 is positioned on 25 the lower extremities of the suction tube 20 to screen the incoming insecticide of foreign materials.

In a greenhouse installation, the devices would 30 be positioned at convenient points along the main 10 so that the spray therefrom could reach all desired plants. Should any section of plants require spraying, it is only necessary for the operator to open the valve 15 and direct the blow tube 18 toward that section. Any imperfectly 35 atomized solution collecting in the shield 19 will drain down the tube 20 into the funnel-like depression 26 in the cap 25, and return to the bottle 24.

40 While the invention has been described as particularly applied to greenhouse use, it is of course not limited to this particular use, nor is it limited to the use of steam for atomizing, as it would operate equally well with compressed air. It will be also found useful for spraying many varieties 45 of liquids and solutions.

While a specific form of the improvement has been described and illustrated herein, it is desired to be understood that the same may be varied, within the scope of the appended claims, 50 without departing from the spirit of the invention.

Having thus described the invention, what is claimed and desired secured by Letters Patent 55 is:—

1. A sprayer unit comprising: a vertical cylindrical pressure head; a blow pipe extending outwardly from said head; an atomizer carried at the outer extremity of said blow pipe; a suction pipe extending downwardly from said atomizer; a bracket member clamped about said pressure head and extending outwardly and downwardly therefrom; a receiving socket formed in said bracket member; a liquid container supported in said socket about said suction tube, said socket comprising: a band surrounding said container; and a hook member extending downwardly from said band and beneath said container.
2. A sprayer unit comprising: a vertical cylindrical pressure head; a blow pipe extending outwardly from said head; an atomizer carried at the outer extremity of said blow pipe; a suction pipe extending downwardly from said atomizer; a bracket member clamped about said pressure head and extending outwardly and downwardly

therefrom; a receiving socket formed in said bracket member; a liquid container supported in said socket about said suction tube; and means for attaching said pressure head to a source of pressure.

3. A sprayer comprising: a horizontal pressure pipe; a nipple extending upwardly therefrom; a valve supported by said nipple; a rotatable connection supported by said valve; a vertical cylindrical pressure head supported by said connection; a removable cap closing said pressure head; an atomizing tube extending outwardly and upwardly from said pressure head; an atomizer carried at the outer extremity of said atomizing tube; a suction tube extending downwardly from said atomizer; a container about said suction tube; and a bracket extending from said pressure head to support said container.
